TIMER

Harold T. Pehr, Miami Beach, Fla.

Application August 15, 1949, Serial No. 110,434

4 Claims. (Cl. 200—38)

1

My invention relates to improvements in timers for automatically opening and closing an electric circuit at predesignated times and has particular relation to such devices as are operated by a clockwork and associated mechanism.

An object of this invention is to provide a new and improved timer adapted to be "plugged" into a conventional type electrical outlet and having means for automatically opening and closing the circuit to a radio, lamp or other appliance attached thereto.

Another object of this invention is to produce a timer which will employ a conventional spring or electrically operated clockwork mechanism and associated mechanism of very simple construction.

Another object is to provide a timer which can be incorporated into the conventional type spring operated alarm clock, without interfering with its conventional use as an alarm clock.

Another object of this invention is to produce a timer which will be very inexpensive to manufacture, yet accurate and durable.

These and other objects and advantages will appear from the following description taken in connection with the drawings.

The invention comprises the novel construction and combination of parts hereinafter described and more particularly pointed out and defined in the appended claims. The presently preferred embodiment of this invention has been disclosed in the accompanying drawings and will be herein described, by way of exemplification only, the invention being limited in its embodiments only by the scope of the appended claims.

In the drawings:

Figure 1 is an isometric view of a timer embodying the invention, showing the method of employment with a radio.

Figure 2 is a front elevational view of the same timer.

Figure 3 is a fragmentary vertical section along line 3—3 of Fig. 1, parts being broken away.

Figure 4 is a fragmentary view along line 4—4 of Fig. 2, parts being broken away and parts in central section.

Figure 5 is a fragmentary isometric view of parts of the timer mechanism, as viewed from the rear, parts being broken away.

Figure 6 is a detail central section of parts of the mechanism which opens the electric circuit.

The preferred embodiment of this invention comprises a conventional spring-operated alarm clock 10 with associated mechanism. However,

2

my invention is equally applicable to an electrically operated clock. The clockwork mechanism is conventional and is not shown. The face 11 of clock 10 has the conventional hour and minute dial 12 and alarm dial 13, and also has a third dial 14. Mechanism, hereinafter described, is associated with dial 13 and serves to close or "make" an electrical circuit. Other mechanism hereinafter described is associated with dial 14 and serves to open or "break" the circuit. An electrical outlet 15 is mounted on the side of clock 10 and an insulated wire 16 runs from outlet 15 to plug 17. A second insulated wire 18 connects outlet 15 with permanent magnet 19 which is mounted on the back of face 11 and insulated therefrom by means of insulation 20. A third wire 21 runs from plug 17 to a second permanent magnet 22, thereby completing the wiring circuit except for the gap between magnets 19 and 22, as shown in Fig. 4. This gap is opened and closed by the "make and break" mechanism hereinafter described.

The "make" mechanism employs the conventional alarm mechanism, consisting of dial 13, indicator 23, shaft 24, knurled knob 25, cam 26, gear 27 and band spring 28. Indicator 23 and cam 26 are both rigidly mounted on shaft 24 so that when the shaft is rotated by means of knob 25, both cam 26 and indicator 23 rotate likewise. Gear 27 and band spring 28 ride on shaft 24 but do not rotate with it. Band spring 28 is riveted to the clockwork frame at 29. Gear 27 meshes with idler 46 which in turn meshes with driving gear 45 which is activated by the clockwork, thereby rotating gear 27. The above conventional mechanism I have added the following. An arm 30 of insulating material is bolted to the free end of spring 28 by means of nut 31 and bolt 32, and is disposed at substantially a right angle thereto. Magnet 22 is rigidly mounted in a hole in the thickened portion 33 of arm 30, so that a portion of the magnet extends out from both sides of the arm.

Cam 26 has a cut away slot 34. Gear 27 has a finger 35 stamped out of the gear so as to project in front of the gear. Finger 35 normally rides on the rear face of cam 26, in such position that the gear is forced against spring 28 so as to maintain the spring in a bent position. However when gear 27 is rotated by the clockwork mechanism so that finger 35 coincides with slot 34 in cam 26, the gear is then free to move forward against the cam. This releases the pressure on spring 28 which straightens out, thereby carrying forward with it the arm 30. This brings

magnet 22 in contact with magnet 19, completing the wiring circuit. After an interval of time depending on the size of slot 34, gear 27 will rotate sufficiently to cam finger 35 out of slot 34, thereby again forcing gear 27 backward on shaft 24 and bending spring 28. This would break the circuit except for the attraction between magnets 19 and 22, which keeps the circuit closed until opened by the "break" mechanism.

The "break" mechanism is somewhat similar to the "make" mechanism. Indicator 36 and cam 37 are rigidly mounted on shaft 38 so that they rotate with it when it is turned by means of knurled knob 39. Gear 40 and band spring 41 ride freely on shaft 38, spring 41 being riveted to clockwork frame at 42. Gear 40 has an integral collar 43 having a cut away slot 44. Gear 40 is driven by the clockwork mechanism through the medium of driving gear 45, idler 46 and idler 47. An arm 48 of insulating material is bolted to the free end of spring 41 by means of bolt 49 and nut 50 and is disposed at substantially a right angle to spring 41.

Finger 51 on cam 37 normally rides on the rear face of collar 43 in such position that gear 40 is forced against spring 41, maintaining the spring in a bent position. However, when gear 40 is rotated by the clockwork mechanism so that finger 51 coincides with slot 44, the gear is free to move backward, releasing the pressure on spring 41, which straightens out, carrying arm 48 backward with it. This causes the free end of arm 48 to press against the free end of arm 30. The pressure of arm 48 is greater than the attraction of the magnets 19 and 22, breaking contact between the magnets and carrying arm 30 backward until the rear face of magnet 22 is attracted to magnet 52, holding arm 30 in the rearward position and breaking the wiring circuit. Magnet 52 is mounted on insulated arm 53 which is rigidly secured to the clockwork frame. After an interval of time depending on the size of slot 44 gear 40 will rotate sufficiently to cam finger 51 out of slot 44, thereby again forcing gear 40 forward on shaft 38, and bending spring 41 forward, carrying with it arm 48.

As shown by the drawings, my invention does not interfere with the operation of the conventional alarm. When alarm button 54 is raised, clapper arm 55 is unlocked by conventional means not shown, so that when latch 56 moves forward with band spring 28, the clapper arm 55 is released permitting clapper 57 to strike bell 58 in the conventional manner.

The device is operated as follows: Plug 17 is inserted or "plugged" in a conventional electrical outlet receptacle 59. A radio 60 or other electrically-operated appliance or device is plugged into outlet 15. Indicator 23 is rotated to indicate the time at which it is desired to close the electrical circuit, so as to turn on the radio. Indicator 36 is then rotated to indicate the time at which it is desired to open the circuit, so as to turn off the radio. At the time set by indicator 23 the "make" mechanism hereinbefore described will close the circuit, turning on the radio. At the time set by indicator 36 the "break" mechanism will open the circuit, turning off the radio.

It should be clear from the above that my invention is applicable for turning on and off various other types of electrically-operated devices such as fans, radios, lamps and other such devices. The term "appliances" is therefore used in the appended claims in a generic sense to include all such devices. It should also be

apparent that the "make" and "break" mechanism might also be called a "switch" i. e. a device for making and breaking a circuit.

Having thus described the invention, I claim:

- 5 1. A timer of the type described comprising a clockwork mechanism, a magnetic switch, means actuated by said clockwork mechanism for closing said switch at a predesignated time, means actuated by said clockwork mechanism for opening said switch at a predesignated time and electrically conductive means adapted to connect a source of electrical power with an electrical appliance through said switch, whereby an energizing circuit is provided for the appliance which 10 is opened and closed by the switch at predesignated times under control of the clockwork mechanism, and in which said switch-closing means comprises a dial, an indicator adapted to designate a time on said dial, cam means controlled by said indicator, a gear operatively associated with said cam and driven by said clockwork mechanism and a resilient arm activated by said cam and gear, whereby at the predesignated time said switch is closed and in which said switch-opening means comprises a second dial, a second indicator adapted to designate a time on said second dial, second cam means controlled by said second indicator, a second gear operatively associated with said second cam and driven by 15 said clockwork mechanism and a second resilient arm activated by said second cam and second gear whereby at the predesignated time said switch is opened, and said switch comprises an insulated arm attached to said resilient arm, a magnetic contact member carried by said insulated arm, a second magnetic contact member in fixed position to one side of said insulated arm and adapted to make contact with said magnetic contact member, a third magnet in fixed position 20 to the opposite side of said insulated arm and also adapted to make contact with said contact member, and a second insulated arm attached to said second resilient arm and operatively associated with said first insulated arm.
- 20 35 2. A timer of the type described comprising a housing, a plurality of electrically conductive members carried by said housing and adapted to be connected with a source of electrical power, an electrical outlet in said housing, a clockwork mechanism in said housing, an alarm mechanism, an electrical circuit connecting said members and said outlet, means for simultaneously actuating said alarm mechanism and closing said circuit actuated by said clockworks, magnetic 40 means for releasably maintaining said circuit closed, circuit-opening means activated by said clockworks, magnetic means for releasably maintaining said circuit open, whereby connection of said members to a source of electrical power 45 provides a circuit for energizing an electrical appliance connected with said outlet which is closed and opened under control of said clockwork mechanism, said alarm-activating and circuit-closing means comprising a dial, an indicator adapted to indicate a selected time on said dial, cam means controlled by said indicator, a gear operatively associated with said cam and driven by said clockwork mechanism and a circuit-closing arm activated by said cam and gear, whereby at the selected time said alarm is activated and said circuit is closed and said circuit-opening means comprising a second dial, second indicator adapted to indicate a selected time on 50 said second dial, second cam means controlled by said second dial, second gear means controlled by said second indicator, a second gear operatively associated with said second cam and driven by said clockwork mechanism and a second resilient arm activated by said second cam and second gear whereby at the selected time said switch is opened, and said switch comprises an insulated arm attached to said second resilient arm, a magnetic contact member carried by said insulated arm, a second magnetic contact member in fixed position to one side of said insulated arm and adapted to make contact with said magnetic contact member, a third magnet in fixed position to the opposite side of said insulated arm and also adapted to make contact with said contact member, and a second insulated arm attached to said second resilient arm and operatively associated with said first insulated arm.
- 55 60 65 70 75

by said second indicator, a second gear operatively associated with said second cam and driven by said clockwork mechanism and a circuit-opening arm activated by said second cam and second gear, whereby at the selected time said circuit is opened.

3. A timer of the type described comprising a clockwork mechanism, an alarm mechanism, an electric switch, means actuated by said clockwork mechanism for simultaneously actuating said alarm mechanism and closing said switch at a predesignated time, means for prohibiting the actuation of said alarm mechanism while permitting the closing of said switch, and means actuated by said clockwork mechanism for opening said switch at a predesignated time, and in which said alarm-operating and switch-closing means comprises a dial, an indicator adapted to designate a time on said dial, cam means controlled by said indicator, a gear operatively associated with said cam and driven by said clockwork mechanism, and a resilient arm activated by said cam and gear, said switch-opening means comprises a second dial, a second indicator adapted to designate a time on said second dial, second cam means controlled by said second indicator, a second gear operatively associated with said second cam and driven by said clockwork mechanism and a second resilient arm actuated by said second cam and second gear, and said switch comprises an insulated arm attached to said resilient arm, a magnetic contact member carried by said insulated arm, a fixed second magnetic contact member positioned to one side of said insulated arm and adapted to make contact with said magnetic member, a third magnet in fixed position to the opposite side of said insulated arm and also adapted to make contact with said contact member, and a second insulated arm attached to said second resilient arm and operatively associated with said first insulated arm.

4. A timer of the type described comprising a clockwork mechanism, an electrical switch, switch-closing means comprising a dial, an indi-

cator adapted to designate a time on said dial, cam means controlled by said indicator, a gear operatively associated with said cam and driven by said clockwork mechanism and a resilient arm activated by said cam and gear, switch-opening means comprising a second dial, a second indicator adapted to designate a time on said second dial, second cam means controlled by said second indicator, a second gear operatively associated with said second cam and driven by said clockwork mechanism and a second resilient arm activated by said second cam and second gear, said switch comprising an insulated arm fixedly attached to said resilient arm, a magnetic contact member carried by said insulated arm, a second magnetic contact member in fixed position to one side of said insulated arm and adapted to make contact with said first contact member, a third magnet in fixed position to the opposite side of said insulated arm and also adapted to make contact with said first contact member, and a second insulated arm fixedly attached to said second resilient arm and operatively associated with said first insulated arm, and electrically conductive means adapted to connect a source of electrical power with an electrical appliance through said switch, whereby an energizing circuit is provided for the appliance which is opened and closed by the switch at predesignated times under control of the clockwork mechanism.
